Patented Oct. 27, 1914.

UNITED STATES PATENT OFFICE.

FRANK ANDRUSZKIEWICZ, OF EASTHAMPTON, MASSACHUSETTS.

WRENCH.

1,115,372.

Specification of Letters Patent. Patented Oct. 27, 1914.

Application filed March 30, 1914. Serial No. 828,293.

To all whom it may concern:

Be it known that I, FRANK ANDRUSZKIEWICZ, a citizen of the United States, residing at Easthampton, in the county of Hampshire and State of Massachusetts, have invented certain new and useful Improvements in Wrenches; and I do declare the following to be a full, clear, and exact description of the invention, such as will enable others skilled in the art to which it appertains to make and use the same.

This invention relates to new and useful improvements in wrenches and more particularly to the character of wrench in which relatively fixed and movable jaws are provided, the same having a pivoted rack catch, and the primary object of the invention is to provide a device of this character in which delicate adjustments may be made.

Still another object of the invention resides in providing a wrench which is so constructed as to permit the movable jaw to be automatically retained in any position to which the same may be adjusted.

A still further object resides in providing an improved means for arranging a spring in connection with the movable jaw and pivoted pawl carried thereon, so that the latter may be normally held in position for engagement with the rack on the shank.

A still further object resides in providing a device which is simple and durable in construction, inexpensive to manufacture, and one which will be very efficient and useful in operation.

With these and other objects in view, my invention consists in the novel features of construction, combination and arrangement of parts as will be hereinafter referred to and more particularly pointed out in the specification and claim.

In the accompanying drawing forming a part of this application: Figure 1 is a side elevation of a device constructed in accordance with my invention; Fig. 2 is a front elevation thereof; Fig. 3 is a side elevation thereof partly in section; and Fig. 4 is a similar view as seen on line 4-4 of Fig. 3.

In describing the invention, I shall refer to the drawing in which similar reference characters designate corresponding parts throughout the several views, and in which 1 indicates a shank, the upper portion of which is designed to provide a fixed jaw 2 and the one side edge of said shank is provided with a plurality of teeth indicated as

3, whereby a rack is formed on this edge of said shank. Slidably mounted on the shank is a housing 4, one portion of which is projected beyond the adjacent side edge of the shank to provide an additional jaw 5, the latter being substantially a movable jaw with respect to the jaw 2. That portion of the housing which is designed to form the jaw 5 is slotted from its lower edge as indicated at 6 and pivotally held in this slotted portion of the jaw is the upper end of a dog 7. This dog has the upper portion thereof reduced in thickness to provide a tongue 8 and it is the latter portion of the dog which is received in the slotted portion 6 of the jaw. The dog 8 is provided with teeth 9 which are designed for engagement with the rack teeth 3 and the pivot of this dog is a pin or stud 10 which is preferably projected slightly beyond the faces of the jaw for a purpose to be hereinafter and more particularly set forth.

It might be here stated that the teeth of the rack 3 are preferably inclined so that the pawl or dog 7 may readily ride thereover in the raising of the movable jaw upwardly with respect to the fixed jaw and I have provided an improved spring means in connection with this dog for the normal retention of the latter in engagement with the teeth. To this end, a channel 11 is provided to extend transversely through the body of the dog 7 adjacent its engaging end and disposed therethrough is a wire spring member 12. This spring member is bent along the side faces of the dog and has the arms thereof extended upwardly along the side faces of the jaw 5. Keepers 13 are provided on the side faces of the jaw through which the arms of this bent spring member are guided and the free ends of the arms of the spring member are bent inwardly as shown at 14 to extend in an additional channel 15 formed in the jaw 5. It is obvious from this construction that the spring member will normally tend to retain the jaw 5 in its effective position and said movable jaw may be readily disposed toward the fixed jaw and held in any adjusted position. It will also be seen, however, that in view of this construction, this movable jaw may not be casually moved in a direction from the fixed jaw, and in order to accomplish the latter result, the jaw 5 must be grasped and thrown outwardly to disengage the teeth thereof from the teeth 3 of the

rack on the shank. I have provided a means in connection with this spring held dog to limit the outward swinging movement of the latter and thus protect the spring member 12 from undue wear. To this end, the bent arms of the spring which are disposed along the side faces of the jaw and the dog are arranged in a plane inwardly and above the pintle or pivot 10 of said dog. As 10 stated above, the ends of this pivot pin project slightly beyond the side faces of the jaw in which the same is disposed, and thus it will be seen that the arms of the spring will contact with the projecting portions 15 of the pivot pin or pintle when the arms of this spring are drawn outwardly and downwardly upon the outward movement of the pawl or dog 7. It will thus be seen that the outward swinging movement of this pawl 20 is somewhat limited by the engagement of the arms of the spring with these projecting portions of the pintle or pivot and the arrangement of the parts is such that the dog may only be swung outwardly to such a degree as will enable the teeth thereof to entirely free themselves from their engagement 25 with the teeth of the rack 3. Undue wear on the spring will thus be prevented, and the life of said spring will be greatly enhanced. It might be here also stated that the shank 1 is provided with a stud 16 at 30 a point below the rack, which stud has its ends projecting beyond the side faces of this shank whereby to limit the downward or outward movement of the housing and movable jaw thereon. The extreme outer end 35 of the shank 1 is reduced and tapered as shown at 17 to form a screw driver and thus when this device is not being used as 40 a wrench, the same may be efficiently used for the purpose of applying screws in objects.

From the foregoing, it will be seen that

I have provided a simple, inexpensive and efficient means for carrying out the objects 45 of the invention, and while I have particularly described the elements best adapted to perform the functions set forth, it is obvious that various changes in form, proportion and in the minor details of construction may be resorted to without departing 50 from the spirit or sacrificing any of the principles of the invention.

Having thus described my invention, what I claim is:

A wrench of the class described comprising a shank, a fixed jaw formed at one end thereof, a relatively movable jaw mounted on said shank, said shank being provided with rack teeth along one side edge thereof, 60 a dog pivotally carried on the movable jaw and designed for engagement with said rack teeth, the pivot pin of said dog projecting slightly beyond the side faces of said movable jaw, a spring member disposed completely through said dog and bent to permit the arms thereof to project upwardly along the side faces of the dog and said movable jaw, and means for securing the ends of the arms of said spring to said movable jaw whereby to normally dispose said dog in its effective engaging position, the projecting portions of said pivot pin being arranged just outside of the plane of the arms of said spring and intermediate the 75 ends thereof for engagement with said arms when the dog is moved to its ineffective and disengaged position whereby to limit the outward swinging movement of the latter.

In testimony whereof I have hereunto set 80 my hand in presence of two subscribing witnesses.

FRANK ANDRUSZKIEWICZ.
Witnesses:

CHAS. H. JOHNSON,
EARL V. GUY.
